[57] CLAIM

The ornamental design for a smoke director for a conveyor oven, as shown and described.

DESCRIPTION

FIG. 1 is a top, rear perspective view of a smoke director for a conveyor oven showing my new design;

FIG. 2 is a right side elevational view thereof, the left side being a mirror image of the shown;

FIG. 3 is a front elevational view thereof;

FIG. 4 is a rear elevational view thereof;

FIG. 5 is a top plan view thereof;

FIG. 6 is a bottom plan view thereof.

The appearance of the left side is a mirror image of that shown in FIG. 2.
